P.A.; Benjamin M. Hanrahan

CLAIM

The ornamental design for a corner bracket for a screen enclosure assembly, as shown and described.

DESCRIPTION

FIG. 1 is a perspective view illustrating my design for a corner bracket for a screen enclosure assembly.

FIG. 2 is a right side view thereof.

FIG. 3 is a left side view thereof.

FIG. 4 is a front view thereof.

FIG. 5 is a rear view thereof.

FIG. 6 is a top view thereof.

FIG. 7 is a bottom view thereof; and,

FIG. 8 is another perspective view with environmental subject matter.

The broken lines illustrated in FIG. 8 represent environmental subject matter that forms no part of the claimed design.

1 Claim, 6 Drawing Sheets
